UNITED STATES PATENT OFFICE.

CHARLES L. GARGAN, OF ROCHESTER, NEW YORK.

GRINDING-MACHINE.

1,172,274.

Specification of Letters Patent. Patented Dec. 22, 1916.

Application filed August 3, 1914. Serial No. 854,740.

To all whom it may concern:

Be it known that I, CHARLES L. GARGAN, of Rochester, in the county of Monroe and State of New York, have invented a new and 5 useful Improvement in Grinding-Machines, which improvement is fully set forth in the following specification and shown in the accompanying drawings.

The present invention relates to a grinding machine and an object of the same is to provide a machine designed for use in automobile garages or other small shop for repairing automobiles and small marine engines preferably of that type in which 15 the cylinders have one end permanently closed.

To these and other ends, the invention consists in certain parts and combinations of parts all of which will be hereinafter described, the novel features being pointed out in the appended claims.

In the drawings: Figure 1 is a vertical section through the machine adjusted for grinding purposes, a cylinder being attached thereto, and parts of the machine being shown in elevation; Fig. 2 is a section on the line *a—a*, Fig. 1; Fig. 3 is a section on the line *b—b*, Fig. 1; Fig. 4 is a sectional view showing the centering device for centering the cylinder upon the machine; Fig. 5 shows a side elevation of the rear end of the machine; Fig. 6 is a detail sectional view of the centering device; and Fig. 7 is a detail view of one of the work supporting devices.

Referring more particularly to the drawings, 1 indicates a frame which may be of any suitable construction. Supported on this frame is an open-ended bearing sleeve 2 which projects from the frame 1 and is provided at its free end with a face plate 3. This face plate may be formed with a plurality of bolt openings so as to adapt it to support a plurality of work-supporting devices 5 which may be substantially Z-shape in form. The two parallel arms of each work-supporting device 5 are provided with slots 6, and bolts 7 pass through these slots and the bolt opening in the plate 3 for securing the work-supporting devices to said plate 3. Against the outer end of these work-supporting devices, the cylinder 8 is adapted to be supported by passing bolts 9 through the slots 6 at the outer ends of the Z-shaped members 5 and through the usual bolt open-

ings in the flange 10 of the cylinder 8 which is the common form used in automobiles and small marine engines, having one end closed and the other end provided with the outwardly-extending flange 10.

Within the bearing sleeve 2, a hollow shaft 11 turns, said shaft being also axially movable within the sleeve 2 and being much longer than the sleeve 2 so as to project from opposite ends thereof. Rotation of this hollow shaft 11 may be effected in any suitable manner but it is preferred to employ a worm wheel 12 which is journaled on the end of the sleeve 2 and held thereto by projections 13 operating within an annular groove in a hub of the worm wheel 12. The worm wheel 12 has a key or rib 14 which operates within a slot 15 of the hollow shaft 11 and communicates motion to said shaft while permitting the shaft to move axially with relation to said worm wheel which may be driven by a worm 16 operated by any suitable means (not shown).

For moving the hollow shaft axially, suitable means may be employed. In this instance, on the inner end of the shaft, two collars 17 are removably secured in spaced relation and, between the collars, a ring 18 is arranged to permit the hollow shaft 11 to turn therein. This ring 18 carries a nut 19 through which operates a screw 20 rigidly supported at 21 on the frame 1 and having a beveled gear 22 thereon meshing with a beveled gear 23 on a shaft 24 which is at right angles to the screw shaft 20. Arranged on the shaft 24 is a clutch sleeve 25 which is axially movable on the shaft 24 but is keyed to said shaft so that said sleeve and shaft turn together. Loosely journaled on the shaft 24 on opposite sides of the clutch sleeve are two beveled gears 26 and 27 both of which mesh with a beveled gear 28 on a shaft 29 which is driven by a pulley 30. When the sleeve 25 interlocks with the beveled gear 26, the shaft 24 is driven in one direction so as to feed the hollow shaft 11 in one direction, and when the sleeve 25 interlocks with the beveled gear 27, the direction of rotation of the screw 20 is reversed as is also the direction of feed of the hollow shaft 11.

The reversal of feed of the hollow shaft 11 may be effected automatically by providing an arm 31 on the nut 19 to operate on a rod 32 which, by a bell crank lever 33,

is connected to the clutch sleeve 25. The rod 32 may have adjustable stops 34 thereon to be engaged by the arm 31 as the latter reaches the end of its movement. The screw shaft 20 may have a crank handle 20^a at one end by which the hollow shaft 11 may be moved by hand when the clutch sleeve 25 is in neutral position.

The hollow shaft 11 is adapted to support the tool and, to this end, its outer end is formed with external screw threads on which a head 35 is adapted to be screwed. This head serves as a support for an adjustable bearing 36 which is in the form of a disk pivoted at 37 on a bolt to swing about an axis eccentric to the axis of rotation of the head 35 and hollow shaft 11, being held in its adjusted position by a bolt 38, which is carried by the bearing 36 and is adapted to work in a slot 39 concentric with the pivot bolt 37. The head 35 is provided with an arc-shaped opening 40 through which a portion of the bearing 36 operates.

The bearing 36 serves as a support for the tool 41 which is preferably in the form of a disk-shaped grinding wheel having a cylindrical periphery. This grinding wheel is supported on a stub shaft 42 which turns in the bearing 36 about an axis parallel with the axis of turning of the head 35 and being adjustable toward and from the axis of turning of said head by the bearing adjustment previously described. This adjustment is provided in order that the periphery of the grinding tool may properly coöperate with the interior wall of the cylinder.

For driving the grinding tool, the shaft 42 of the latter may be connected by a universal joint 43 to a shaft 44 which, in turn, is connected by a universal joint 45 to a shaft 46 journaled on the main frame of the machine. The shaft 44 turns within the hollow shaft 11 and the shaft 46 is axially movable on the main frame of the machine, being, for this purpose, provided with a longitudinally-extending groove which receives a key on a pulley 48, the pulley 48 being supported on the main frame of the machine against axial movement.

For centering the hollow shaft 11 with relation to the cylinder 8 there may be employed a centering device which preferably is in the form of a split cone 49 having its members held together by screws 50 to clamp the cone upon the hollow shaft 11 in rear of the head 35. This centering device is adapted to be moved into the open end of the cylinder 8 while the latter is loosely supported on the supporting devices 5, and after the cylinder is properly centered, the cylinder is firmly clamped or bolted to the supporting devices 5, and then the centering device may be removed from the hollow shaft 11.

When the machine is used for grinding

the interior of hollow cylindrical bodies, the cylinder 8 is first loosely secured to the work-supporting devices 5 and the centering device 49 is introduced into the open end of the cylinder 8 in a manner shown in Fig. 7c 4. After the cylinder is centered, it is rigidly secured in its centered position and the centering device is removed from the hollow shaft 11. The rotary grinder is then caused to engage the interior wall of the cylinder in proximity to the open end of the latter and the different mechanisms are started to rotate the shaft 11, feed the shaft 11 axially and rotate the shaft 42, causing the grinding disk 41 to advance toward the closed end of the cylinder, revolve about the axis of the shaft 11 and rotate about its own axis thus traveling over the interior of the cylinder in a helical path. When the inner end of the cylinder is reached, one of the stops 34 is engaged, causing the shaft 11 to travel axially in the opposite direction in order to carry the grinding tool toward the open end of the cylinder.

From the foregoing, it will be seen that there has been provided a machine which is adapted for internal cylindrical grinding. The grinding tool which is in the form of a cylindrical disk has its cylindrical periphery traveling in a helical path in contact, throughout its width, with the interior cylindrical surface. This is secured by having the grinding disk turn about an axis parallel with the axis about which it revolves and feeding the grinding disk in the direction of its axis of revolution. The axis of rotation is adjustable toward and from the axis of revolution so that proper engagement between the periphery of the grinding tool and the wall to be ground may be maintained. The machine is especially adapted for operating upon cylinders which are opened at one end only, and novel means is employed for rigidly supporting the cylinder upon the machine. Provision is also made for properly centering the cylinder upon the machine, this means being removable so that it is unnecessary to remove the grinding tool before starting on the grinding operation.

While the invention has been described as a grinding machine, it is apparent that certain parts of the machine may be employed in other machines.

What I claim as my invention, and desire to secure by Letters Patent is:

1. In combination with a suitable support, a rotary hollow shaft mounted for axial movement on said support, a rotary grinder having its axis of rotation parallel with the axis of rotation of the shaft and adjustable in parallel lines toward and from the axis of rotation of the hollow shaft, means extending through said shaft for rotating the grinder with the rotation of the hollow

shaft, and independently adjustable work supporting devices secured to the support about the hollow shaft.

2. In combination with a main frame having a rigid sleeve projecting therefrom and formed with a flange at its free end, means for securing the work piece to said flange, a rotary hollow shaft movable axially within said sleeve, an adjustable bearing on said shaft, a shaft turning in said bearing, a tool on the shaft, and means extending through the hollow shaft and connected to the tool shaft for rotating said tool.

3. In combination with an open ended bearing sleeve, work securing devices attached to one end of the sleeve, a hollow shaft turning in said sleeve and axially movable therein, a rotary grinder mounted on said hollow shaft and adjustable toward and from the axis of rotation of said hollow shaft, and means extending through the hollow shaft for driving the grinder.

4. In combination with an open-ended bearing sleeve having a flange at one end, 25 Z-shaped work supports adjustably secured to said flange, and a rotary tool carrying shaft mounted to turn in said sleeve and axially movable therein, and centering means removably secured to said shaft.

5. In combination with a main frame having a rigid open-ended sleeve projecting therefrom and formed with a flange at its free end, means for securing the work to said flange, a shaft mounted to turn in said sleeve and also to move axially therein, said shaft projecting from opposite ends of the sleeve, a tool carried by one end of said shaft, a gear wheel mounted on the main frame at the other end of said sleeve, and 40 having the shaft connected thereto to move therewith but to permit the shaft to move axially with relation to said gear wheel, means for moving the shaft axially, and means for turning the gear wheel to turn the shaft.

6. In combination with a main frame, a rotary tool carrying shaft mounted for axial movement on said main frame, means for rotating the shaft, and means for moving the shaft axially comprising a drive shaft, a bevel gear on the drive shaft, a shaft at right angles to the drive shaft, a pair of bevel gears mounted to turn loosely on the second mentioned shaft, a clutch adapted 55 to connect either of said pair of beveled gears to the second mentioned shaft, connection between said second mentioned shaft and the axially movable shaft to effect such axial movement, a bell crank lever having 60 one arm connected to the clutch, a rod connected to the other arm of the bell crank lever, stops on said rod, and means moving with the axially movable shaft and operating between the stops to effect the shifting 65 of the clutch.

7. In combination with a main frame, a rotary tool carrying shaft mounted for axial movement on the main frame, means for rotating the shaft, and means for moving the shaft axially comprising a drive shaft, a 70 beveled gear on the drive shaft, a shaft at right angles to the drive shaft, a pair of beveled gears mounted to turn loosely on the second mentioned shaft, a screw shaft driven by said second mentioned shaft, a member 75 in which the rotary axially-movable shaft turns, having the screw shaft connected thereto, a clutch adapted to connect either one of the pair of beveled gears with the beveled gear on the drive shaft, a bell crank 80 lever having one arm connected to the clutch, a rod connected to the other arm of the bell crank lever, and adjustable stops on said rod between which operates the member which is moved by the screw shaft. 85

8. In combination with a suitable support, a rotary hollow shaft mounted for axial movement on said support and having a head at one end, a bearing disk pivoted on said head to move transversely of the axis 90 of the hollow shaft about an axis eccentric to the axis of the hollow shaft and a rotary tool carried by said bearing disk.

9. In combination with a suitable support, a rotary hollow shaft mounted for 95 axial movement on said support, means for rotating the shaft, means for moving the shaft axially during such rotation, a bearing member adjustably supported on said hollow shaft to move transversely of the axis 100 of said shaft, a tool shaft mounted on said bearing member with its axis parallel to the axis of the hollow shaft, a tool carried by said shaft, and means for rotating the tool shaft embodying a shaft section extending 105 through the hollow shaft and having a universal joint connection with the tool shaft at one end, and a shaft section having a universal joint connection with the first mentioned shaft section at its other end. 110

10. In combination with a main frame having a rigid sleeve projecting therefrom, means for supporting work from the outer end of said sleeve, a hollow shaft turning in said sleeve, means for rotating the shaft, 115 means for moving said shaft axially during such rotation, a bearing member adjustable on said hollow shaft transversely of the axis of said shaft, a shaft carried by said bearing member with its axis parallel to the axis of rotation of the hollow shaft, a tool carried by said shaft, and means for rotating the tool shaft, said means extending through the hollow shaft, and having universal joints 120 permitting the adjustment of the tool on the hollow shaft. 125

11. A machine of the class described comprising a main frame having a rigid sleeve provided with a flange at one end, substantially Z-shaped supports having bolt and 130

slot connections with the flange, a hollow shaft arranged to turn within said rigid sleeve and also to move axially, and a rotary tool eccentrically supported on said hollow shaft.

12. A machine of the class described comprising a main frame, spaced work supports on said frame, a shaft arranged centrally of said supports and movable axially, a tool carried by said shaft, and a split cone-shaped centering device secured to said shaft in rear of the tool and removable between the supports after the work has been clamped to the supports.
13. A machine of the class described comprising a main frame, spaced work supports adjustably mounted on the main frame and

adapted to be adjustably connected to the work, a shaft arranged centrally of said support and movable axially, a tool carried by said shaft, and a centering device secured to the shaft for centering the work on the spaced supports.

14. A machine of the class described comprising work supporting means, a shaft movable axially, a tool carried by said shaft, and work centering means also carried by said shaft to center the work on the work supporting means. 25
